D. L. DAVIS

FOUNTAIN PEN

Filed Oct. 10, 1924

Inventor
David L. Davis
By William Leonard

UNITED STATES PATENT OFFICE.

DAVID L. DAVIS, OF FORT MADISON, IOWA, ASSIGNOR TO W. A. SHEAFFER PEN COMPANY, OF FORT MADISON, IOWA, A CORPORATION OF DELAWARE.

DESIGN FOR A FOUNTAIN PEN.

Application filed October 10, 1924. Serial No. 11,013. Term of patent 3½ years.

To all whom it may concern:

Be it known that I, DAVID L. DAVIS, a citizen of the United States, residing at Fort Madison, in the county of Lee and State of Iowa, have invented a new, original, and ornamental Design for a Fountain Pen, of which the following is a specification, reference being had to the accompanying drawing, forming part thereof.

The figure is a plan view of a fountain pen, showing my new design.

I claim:

The ornamental design for a fountain pen, as shown.

Fort Madison, Iowa, September 26th, 1924.
